GAME

Lester Engel, Indianapolis, Ind.

Application November 6, 1937, Serial No. 173,216

4 Claims. (Cl. 273—94)

This invention relates to games and has for its primary object the provision of a structure permitting the exercise of skill and accuracy in playing the game and also in the provision of an extremely simple structure which may be supplied to the trade in a convenient form ready to be set up without the exercise of mechanical skill.

These and other important objects and advantages of the invention will become apparent to those versed in the art in the following description of the invention as shown in one particular form in the accompanying drawing, in which

15 Fig. 1 is a top plan view of the playing field; Fig. 2 a detail in perspective of a goal; and Fig. 3 a top view in perspective of the playing elements.

Like characters of reference indicate like parts 20 throughout the several views in the drawing.

Referring to the drawing, a course or field 10 is supplied preferably in the nature of a sheet of paper or board which may be positioned in extended condition to present a flat course. The 25 course is provided with a central transverse divided line 11, centrally of which in the center of the course is marked off a rectangular starting area 12 having an equal area on each side of the line 11. The starting area 12 is provided with a circular area 13 and 14 marked off therein on the respective sides of the line 11, each circular area being centrally positioned within that part of the area 12 on its side of the line 11.

35 The course 10 is further provided with the transverse lines 15 and 16 extending entirely across the course 10 toward the ends of the course to define respectively between the center line and the end of the course a "penalty area".

40 In each of the "penalty areas" there is located the respective "penalty kick marks" 19 and 20, herein shown as circular areas defined by circular lines.

On each end of the course centrally positioned 45 transversely along the "penalty area" is a goal consisting essentially of two upright members 21 and 22 in the nature of goal posts, the members 21 and 22 being further tied together by the cross bar 23 at a distance above the course,

50 Fig. 2. In the form herein shown, these goal posts 21 and 22 and the cross bar 23 are formed integrally with the course 10 in such a manner as to fold upward into position from initial flat extended positions. In Fig. 1, these members 55 are shown in their original flat positions where-

as in Fig. 2, the members are shown as being folded to their upright, playing positions.

Referring further to the goal structure, the posts 21 and 22 in the form herein shown are provided with wings 24 and 25 respectively which may be folded rearwardly as in Fig. 2 to serve as braces to maintain the posts 21 and 22 in their upright positions. Furthermore the cross bar 23 may, as herein shown, be reinforced by the outer or rear flange 26 which may be turned 10 rearwardly from the bar 23 as in Fig. 2. In using this particular form of a goal, the course 10 is preferably supplied to the user with the various members in the flat, extended positions within the plane of the course as indicated in 15 Fig. 1. The fold lines between the wings 24 and 25 of the flange 26 may be defined by scoring or the like on the dash lines as indicated in Fig. 1. The lines defining the junctures of the wings 24 and 25 with the end of the course 10 20 are preferably initially cut through as is also the line following the inner sides of the posts and the bar 23. Thus when the members are erected to the upright positions, there will be left a tab 27 extending between the goal posts 25 from the "penalty area" and in the same plane as that of the course. This tab 27 thus presents a part of the course in the same plane without offering any offset or shoulder as the playing pieces may pass between the goal posts. The 30 elements employed to play the game consist of a circular disc 28 termed the "ball" and two circular discs 29 and 30 preferably of a larger diameter although any distinguishing means may be employed as between these members 29, 30 35 and the member 28.

To use the structure above defined, the following rules are employed. The game shall last until one of the two players has scored four goals. The game is begun by one of the two players 40 selected to start, such as by flipping a coin. The "ball" 28 is placed on one of the two circular areas 12 or 13 depending on which goal is being defended by the other player, the position 13 or 14 being selected to be on the side of the line 45 11 opposite the defended goal.

The player commencing the game then has the option of placing the piece 29 or 30 whichever he has selected, hereinafter termed "flipper" on any position on the end line of his side of 50 the starting rectangle 12. The opposing player must place his "flipper" on the other circular area within the starting rectangle. Play commences on the course 10 when the starting player flicks his "flipper" against the "ball" toward his 55

opponent's goal. The next play consists of the opposing player flicking his "flipper" towards or at the "ball", striving to defend his opponent's territory to score a goal. Each player is allowed one flick at a time and the players alternate flicking until a goal is scored. A goal is scored when the "ball" 28 passes between the goal posts 21 and 22 and over the line therebetween of either player's goal area.

10 After each goal is scored, the players return to the starting area 12 and put the "ball" 28 into play again with the player scored upon last then commencing play. When a player flicking toward its opponent's goal flicks the "ball" 28 over the goal line at the end of the course, but not between the goal posts 21, 22, no goal shall be scored and the defending player is given the opportunity to put the "ball" 28 into play from any point on his goal line where the "ball" 28 passed out of bounds. The opposing player, at such times, must place his "flipper" 29 or 30 as the case may be, on the circular area 19 or 20 which appears on his side of the starting rectangle and there await the flick of his opponent.

15 No goal may be scored, however, in a single shot when the "ball" 28 is thus put into play. It is evident that at least two flick shots must be taken alternately before a goal may be scored when the "ball" is thus put into play by the defending player.

If in the course of the game, the "ball" is flicked out of bounds (across the dash side lines) by either player, his opponent is allowed to put the "ball" 28 into play at exactly in the corresponding spot on such side line 17 or 18 as the case may be, and the play proceeds from that spot. If a player flicks his "flipper" out of bounds he is permitted to place it back on the course at exactly the spot where it went out of bounds and await his turn to flick therefrom.

20 There is a penalty in striking an opponent's "flipper" without first striking the "ball" 28 and this penalty is a free flick against the player who committed the "foul". The penalty flick is made from the spot where the "foul" occurred. The player against whom the penalty is evoked must place his "flipper" on the penalty place kick circle 19 or 20 as the case may be immediately in front of his own goal area and await there the free flick shot of his opponent. If, however, the "foul" occurs within the area marked "penalty area", the penalty flick shot is awarded to the "fouled" player from the penalty place kick circle 19 or 20 regardless of where the "foul" occurred within this area. The player against whom the penalty is evoked at such times must place his "flipper" on his own goal line on any spot between his goal

posts and there await the free flicked shot of his opponent. A goal may be scored in a single flick by the "fouled" player regardless of where the "foul" may have occurred.

While I have herein shown and described my invention in the one particular form, it is obvious that structural changes may be employed without departing from the spirit of the invention, and I therefore do not desire to be limited to that precise form beyond the limitations as may be imposed by the following claims.

I claim:

1. In a game having a playing board comprising a flat rectangular field having side-lines set in from its edge and a bounded central starting area having a central transverse line passing through the area and having a bounded penalty area at each end of the field, a goal at each end of the field located centrally of the respective penalty areas, each of said goals comprising a pair of post members hinged to the board and brace members hinged to swing into position to retain the posts in upright positions.

2. In a game having a playing board comprising a flat rectangular field having side-lines set in from its edge and a bounded central starting area having a central transverse line passing through the area and having a bounded penalty area at each end of the field, a goal at each end of the field located centrally of the respective penalty areas, each of said goals comprising a pair of post members hinged to the course and brace members hinged to swing into position to retain the posts in upright positions, and said board having a tab extending between the posts to remain as a flat extension of the board.

3. In a game, having a flat board with starting and penalty areas defined thereon, goals at each end of the board initially formed as an integral part thereof, each goal consisting of a pair of post members hinged to the board end, a cross bar joining the posts at a distance from the board, and a tab left between the two posts and cross bar to form a field extension between the posts.

4. In a game, having a flat board with starting and penalty areas defined thereon, goals at each end of the board initially formed as an integral part thereof, each goal consisting of a pair of post members hinged to the board end, a cross bar joining the posts at a distance from the board, and a tab left between the two posts and cross bar to form a field extension between the posts, and swing brace members hinged along the outer sides of said posts, to bend from the posts to support them vertically.

LESTER ENGEL.
